Patented July 29, 1919.

UNITED STATES PATENT OFFICE.

THEODORE SWANSON, OF LYNN CENTER, ILLINOIS.

ICE-FORMER DEVICE.

1,311,723.

Specification of Letters Patent. Patented July 29, 1919.

Application filed January 18, 1918. Serial No. 212,436.

To all whom it may concern:

Be it known that I, THEODORE SWANSON, a citizen of the United States, residing at Lynn Center, in the county of Henry and State of Illinois, have invented a new and Improved Ice-Former Device, of which the following is a specification.

My invention is in the nature of a mold or form for domestic purposes by the use of which natural ice is frozen in blocks or cakes for refrigerators and my said invention primarily has for its purpose the production of an ice mold or forming device of an exceedingly inexpensive and simple construction, that can be readily applied for use by any one and by which solid form ice cakes are quickly produced, as desired.

Another object of my invention is to provide an ice forming device in which the parts are of such arrangement that danger of the ice cake bulging or cracking, as it freezes solid, is prevented, and the several parts that constitute the form may be readily spread to provide for quickly and conveniently removing the solid ice cake or block therefrom.

With other objects in view that will be hereinafter explained, my invention is a device for the purpose stated that embodies the peculiar features of construction and combination of parts outlined in the following description, specifically pointed out in the appended claim and illustrated in the accompanying drawings, in which:

Figure 1 is a perspective view that illustrates my ice forming device as in practical use.

Fig. 2 is a vertical section of the same and shows the manner in which the bottom closure for the device is formed prior to freezing the ice block or cake.

Fig. 3 is a similar view that illustrates the manner in which the cone works up during the formation of the ice body or block.

Fig. 4 illustrates the manner in which the ice forming device is spread to permit the removal of the solid ice cake, and

Fig. 5 illustrates the manner in which the parts that constitute my ice forming device are arranged for shipping.

My ice cake forming device, which is particularly adapted for use in cold weather for forming ice cakes for refrigerators consists of a bottom piece or blank 1 whose corner edges are slit as at 10 and preferably formed of stiff sheet metal (galvanized

iron) and a body portion 2 formed up from a single sheet of galvanized iron.

In shaping up the parts 1 and 2, the edges 11 of the said bottom 1 are bent up about one-half an inch to form a trough-like member, as is clearly shown in the drawings.

The body sheet 2 is bent to form the four sides or members 20—20 and the ends of the said body piece 2 are bent out at right angles to form vertical flanges 21—21 and, when shaping up the device, the said flanges 21 are clamped fluid tight between two wooden blocks or strips 3—3 that are provided with apertures 30—30 to receive the clamp bolts 4—4 that also pass through edge notches 5—5 in the body flanges 21—21 and are secured for clamping the said parts together by nuts 6—6, as shown.

The body sheet 2, when bent to form the four sides 20, has the horizontal shape of the trough-like bottom 1, but the said body that is formed by bending up the sheet 2, is sufficiently smaller than the bottom 1, whereby, when it is set in place of the trough-like bottom 1, a water receiving space surrounds the bottom edge of the form or body composed of the sides 20, as is clearly shown in Figs. 1 and 2; by reference to which it will be also observed the bottom edge of the vertical flanges 21 are notched, as at 22, which notches register with like notches 33 on the lower ends of the two wooden clamping strips 3—3.

By forming the lower ends of the flanges 21 and the strips 3—3 with the notches 22 and 33, as stated, the form or body is held properly positioned with its four sides spaced from the coincident flanged portions 11—11 of the trough-like bottom 1.

In using the device, the body 2 is set into the body 1. Water is then poured into the trough-like bottom sufficient to close the joint between the body and the said bottom, which, when frozen, makes a water tight joint for the bottom of the mold or former.

The former or mold is then filled with water, preferably ice cold water, since if water taken from the well is used, it will melt the ice seal at the bottom. The quickest results are had by having a tank with ice cold water at hand when filling the form or mold.

To prevent the ice block or cake as it freezes solid within the form or mold 2 from bulging or cracking, I use a core 7 of some element that maintains a temperature

above freezing and which is supported within the mold or form.

In practice I have found that a bottle filled with kerosene oil forms a simple, inexpensive and easily provided core member.

When setting up the device for use, to get the best results, it should be mounted upon a base composed of 2" by 4" side timbers joined by cross slats, since by supporting the ice forming device thereon, ample space is provided for the circulation of cold air under the bottom and sides of the device and, further by providing a base support, as stated, several of the ice forming devices 15 may be supported upon the one base.

The core 7 is hung to project down into the form 2, in such manner that it is free to rise up. In using the device, the core 7 is suspended in any suitable manner with its 20 bottom about midway the height of the mold.

The filled bottle, which constitutes a solid core, serves to prevent the cake forming solid around the bottle, the top surface of the water tends to freeze solid around the bottle, for the reason that as the body of the 25 cake forms and bulges, it pushes the bottom of the bottle up and thereby gives more room for water left in the center of the 30 cake to freeze, it being understood that the tendency of the lateral expansion of the ice cake is taken care of by the constant filling up of the space left under the core as it is being pushed up by the solid ice cake that 35 continuously forms under the bottle or core.

After the water is frozen into a solid cake, as stated, the said cake is readily removed by loosening up the nuts and clamp bolts and removing the wooden strips. 40 The edges of the body at one side can then be sufficiently spread to allow for pulling the mold or form from the ice cake. Should the sides of the form tend to stick to the cake, they can be easily loosened with a 45 thin table knife.

My device is especially useful in places where artificial ice is not to be had.

It is understood that in marketing my invention, only the bottom 1, the body 2, the nutted clamp bolts and strips and the core support are assembled, since the core member can be readily supplied by the user.

My device is as a new article in which the parts 1 and 2 may be packed flatwise with the nutted clamp bolts and the clamp strips, see Fig. 5, it being understood the simplest kinds of instructions accompanying the said parts will enable the user to quickly put the parts into operative condition.

What I claim is:

As a new article, a knock-down ice cake former comprising a flat square shaped resilient metal plate whose corners are split inwardly to a bending line, whereby, when 65 the edges of the said bottom plate are bent up, the said bottom plate assumes a trough shape, the body plate having such length relatively to the bottom plate, whereby when bent to form four sides to constitute 70 the body form, the said body form can be loosely set within the bottom trough, the said body plate including end extensions, each formed with edge notches and a notch in the bottom end, the said extensions being 75 foldable against each other and adapted to rest over the upper edge of one of the trough sides, and a pair of clamping strips, each having a notch in the lower end for fitting onto the upper edge of the aforesaid 80 trough sides and having bolt apertures that align the edge notches in the body extensions, when the parts are assembled for use, and nut and bolt devices for clamping the strips and the end extensions of the body together, the lower edge of the said clamping strips constituting a means for holding the 85 formed body spaced from the sides of the trough shaped body, as specified.

THEODORE SWANSON.
